UNITED STATES PATENT OFFICE.

I. C. EMERY, OF BALTIMORE, MARYLAND.

LOCK NUT AND BLANK THEREFOR.

Application filed July 15, 1924. Serial No. 726,135.

To all whom it may concern:

Be it known that I, I. C. EMERY, a citizen of the United States, residing at Baltimore city, State of Maryland, have invented certain new and useful Improvements in Lock Nuts and Blanks Therefor; and I do hereby declare the following to be a full, clear, and exact description of the invention, such as will enable others skilled in the art to which it appertains to make and use the same.

This invention relates to lock nuts and has for its object to improve the construction of devices of this character in a manner that will make them more efficient than has been heretofore proposed.

With this and other objects in view, the invention consists in the novel parts and combinations of parts constituting the improved nut, all as will be more fully herein disclosed and particularly pointed out in the claims.

Referring to the accompanying drawings forming a part of this specification, in which like numerals designate like parts in all the views,

Figure 1 is a perspective view of a blank strip of steel suitable for forming the nut constituting this invention;

Figure 2 shows a blank of Fig. 1, partially bent into shape to form the desired nut;

Figure 3 is a plan view of the completed nut;

Figure 4 is a side elevational view of the parts shown in Fig. 3;

Figure 5 is a sectional view of the parts shown in Fig. 4; and

Figure 6 is an enlarged partial sectional elevational view of the nut shown in Fig. 3 with a bolt threaded therethrough.

1 indicates a steel blank from which the nut of this invention is to be made, and said blank is provided on its end portion 2 with the surface 3 which is inclined to the parallel sides or surface 4, as indicated. Said surface 3 on one side terminates in the rounded or curved surface 5 which, in turn, is inclined to the parallel faces 4 of the blank and which terminates in the straight edge 6 located on the extreme edge portion of the hook-like member 7, all as will be clear from the drawings. The opposite end portion 8 of the blank strip 1 is similarly shaped, but the parts, although they are lettered the same as at the end portion 2, are inclined in directions different from said

parts on the end portions 2. The end portions 2 and 8 of the blank strip 1 are also cut away to form the flat surfaces 9 and the spaces 10, as well as the shoulders 11, the surfaces of which are inclined to the parallel faces 4 of the blank, to coact with the inclined surfaces 3 when the blank is formed into a nut.

The blank strip 1 being shaped as just disclosed, may be bent around a mandrel (not shown) into the form illustrated in Fig. 2. After the strip 1 is thus shaped as is shown in Fig. 2, the hook members 7 may be still further bent in any suitable and well known type of machine to complete a circle and until they pass over each other and occupy the spaces 10. When said hook members are thus bent into a circular form, as described, each surface 5 will contact with a cut away surface 9 and the hooks 7 will be disposed opposite each other, all as will be clear from an inspection of Fig. 4. After the hooks 7 have thus been engaged, it is preferred to subject the blank nut thus formed to such a compressive action as will cause the metal to be profoundly displaced until the nut takes on the hexagonal shape illustrated in Figs. 3 and 4, or until it takes on some other desired shape, whose dimensions will be accurate and accord with a predetermined standard. But the original dimensions of the surfaces 5 and of the cut away surfaces 9 are so chosen that even after this heavy compression of the metal, said surfaces 5 will not quite fill up or occupy all of the space provided by the surfaces 9. That is, as is indicated on an exaggerated scale in Fig. 4, after said heavy compression has taken place, there will still be a slight unfilled space 15 between the hooks 7 which will permit the parts to expand when forced to do so, all as will be more fully explained below.

After the nut is thus formed as indicated in Figs. 3 and 4, it is screw threaded. But, it should be said that in forming the blank nut around the above mentioned mandrel, said mandrel is preferably so shaped that its diameter is slightly larger in those portions which will come opposite the portions 16 and 17 of the finished nut than in those portions that will shape the middle 21 of the bore. That is to say, the bore of the blank nut will be shaped somewhat like a double cone and will be somewhat larger in diameter at the respective edges 16 and 17

of the nut than in the middle of the nut. The bore of the nut being thus enlarged slightly at each edge of the same, said bore is next screw threaded with a tap, which is 5 cylindrical or of the same diameter throughout and which has a diameter very slightly less than is the diameter of the screw threaded portion of the bolt 23 which is to be used with the nut. The result is that the 10 screw threads at 19 and 20 near the respective ends of the bore are not complete threads, but are what we might call partial threads having their apices cut off as shown at 19 and 20, Fig. 6. It results that the first 15 thread of the bolt 23 will readily enter the nut, and when said bolt is turned said thread will exert a wedging action on the edge portion 16 on the inside of the nut and cause the other threads of the bolt to follow. 20 But in order for the nut to be screwed home on the bolt more or less force will be required, because the diameter of the bore across the central threads 21 is slightly less than the corresponding diameter of the bolt 25 across its central threads. The result of thus forcing the nut 22 having its central threads 21 of a less diameter than the threads of the bolt, is to force outwardly the parts 7 of the original blank 1, and to thus 30 tend to close up the space 15 in Fig. 4. In other words, the hook portions 7 will tend to approach each other when the finished nut is screwed home and the spring action of the parts will thus tend to normally compress the nut upon the bolt threads to such 35 a degree as to firmly lock the nut in place on the bolt.

It will thus be seen that owing to the threads 19 and 20 being cut away so to 40 speak, or of a somewhat larger diameter than are the threads 21, the bolt 23 can readily enter the nut, while when force is used to thread the nut 22 onto the bolt 23, the compressive action of the parts is brought 45 into action and the nut is firmly locked in place.

The difference in diameters of the bore of the nut and across the threads of the bolt is slight in any case, but will depend 50 upon how accurately to standard dimensions the bolts are made. That is, with nuts that are to be made to standard dimensions and to be accurate within a few thousandths of an inch, and with bolts that are to be made 55 accurate within like narrow dimensions, the diameters of the bores of the nuts need only be a few thousandths of an inch less than the diameters of the bolts. But where the bolts vary in diameters greater than this, 60 the nuts will be given a somewhat wider difference in diameters of bores. In all cases, the enlargements at the ends of the bore need not be greater at each end of a diameter than one-half the depth of a full

thread. It will be clear that the hook portions 7 constitute an important feature of 65 this invention, for when once engaged as in Fig. 4, they cannot be separated, and therefore the strength of the nut and its life is 70 prolonged.

What is claimed is:—

1. A lock nut blank consisting of a strip of metal having flat sides and each end of which is formed with an integral hook-like portion provided on its outside with a curved 75 surface inclined to said sides, and on its inside with a cut away surface forming a space and a shoulder to receive the hook-like portion of the other end.

2. A lock nut consisting of a single, integral strip of metal bent and compressed into shape and provided with a slit extending from the top of the nut downward and curved to a point below the center plane thereof, thence horizontally, thence upwardly to a point above said center plane, thence horizontally again, thence downward and curved to the bottom of said nut providing 85 two interlocking hook portions separated by said slit and a space.

3. A lock nut consisting of a single, integral strip of metal provided with a slit extending from the top of the nut downward and curved to a point below the center plane thereof, thence horizontally, thence upwardly to a point above said center plane, thence horizontally again, thence downward and curved to the bottom of said nut, said nut 95 having two interlocking hook portions separated by a space, and provided with a threaded bore slightly larger at each end than in its central portions.

4. A lock nut consisting of a single, integral strip of metal compressed into shape and having a slit extending from the top of the nut downward and curved to a point below the center plane thereof, thence horizontally, thence upwardly to a point above said center plane, thence horizontally again, thence downward and curved to the bottom of said nut, said nut 105 providing two separated oppositely disposed interlocking hook portions and a bore which is slightly larger at one end than in its middle portions.

5. A lock nut blank consisting of a strip 115 of metal having flat sides and each end of which is formed with an integral hook-like portion provided on its outside with a curved surface inclined to said sides, on its inside with a cut away surface forming a space and a shoulder to receive the hook-like portion of the other end; and each end portion also provided with a surface inclined to said sides and adapted to coact with said curved surface.

In testimony whereof I affix my signature.

I. C. EMERY.
